[57] CLAIM

The ornamental design for a combined garbage disposal plunger and scraper, shown and described.

DESCRIPTION

FIG. 1 is a perspective view taken from the bottom and front of a combined garbage disposal plunger and scraper showing my new design;

FIG. 2 is a rear elevational view thereof;

FIG. 3 is a left side elevational view thereof;

FIG. 4 is a right side elevational view thereof;

FIG. 5 is a bottom plan view thereof; and

FIG. 6 is a top plan view thereof.
